ELECTRICAL CONTROL BOX

W Arthur Ernst, Racine, Wis.

Application March 6, 1958, Serial No. 49,925

Term of patent 14 years

(Cl. D26—13)

Fig. 1 is a front elevational view of an electrical control box showing my new design;

Fig. 2 is a top view thereof;

Fig. 3 is an end elevational view, the opposite end being the same;

Fig. 4 is a bottom view; and

Fig. 5 is a fragmentary sectional view taken along the line 5—5 of Fig. 1.

I claim:

The ornamental design for an electrical control box, substantially as shown and described.
